UNITED STATES PATENT OFFICE.

ALPHONSUS FIEN, OF NEW YORK, N. Y., ASSIGNOR TO S. H. POMEROY COMPANY, INC.,
OF NEW YORK, N. Y., A CORPORATION OF NEW YORK.

METAL WINDOW.

Application filed July 29, 1925. Serial No. 46,725.

To all whom it may concern:

Be it known that I, ALPHONSUS FIEN, a citizen of the United States, residing in the borough of the Bronx, of the city of New York, in the State of New York, have invented certain new and useful Improvements in Metal Windows, of which the following is a specification, reference being had to the accompanying drawing, forming a part hereof.

In hollow metal window frames made of sheet metal, the point of weakness (if any such there be) in the jamb, both structurally and as to weather-tightness, as such windows have been constructed heretofore, has been at the line of the meeting rails of the two sashes in a double-hung window. It has, therefore, been the object of this invention to strengthen the jamb at this point and this purpose is accomplished by the means which will be fully described hereinafter with reference to the accompanying drawing in which the invention is illustrated and in which:

Figure 1 is a view in sectional elevation of so much of a window as is necessary to enable the invention to be understood, a portion of the bottom sash being shown in operative relation with the left-hand jamb and a portion of the upper sash being shown in operative relation with the right-hand jamb, the plane of section of the left-hand jamb and sash being indicated by the broken line 1—1 of Figure 2.

Figure 2 is a view in horizontal section on the plane indicated by the broken line 2—2 of Figure 1.

Figure 3 is a view in section on the plane indicated by the broken line 3—3 of Figure 1.

Figure 4 is a face view showing the jamb, the pulley stile and the strengthening block, as seen in elevation from the right-hand in Figure 1.

Figure 5 is a detail view in elevation of the strengthening block.

In the embodiment of the invention illustrated, the jamb is shown as having its main part *a* formed of sheet metal bent in usual form, as clearly indicated in Figure 2, and a removable, grooved pulley stile, made in two parts *b*, *b*¹, upper and lower, but otherwise formed as usual, to engage the main body *a*, as indicated in Figure 2. Vertical channels or grooves *a*¹, *a*², *a*³, *a*⁴ are formed, as usual,

in the face of the jamb for co-operation with the vertical edges of the upper and lower sashes *c* and *c*¹. Heretofore the jamb has been stiffened only by internal braces, one of which is shown at *d* in each jamb, the pulley stile *b*, *b*¹ being secured to the body of the jamb by a screw passed through the pulley stile into the brace.

In accordance with the present invention, the removable, grooved pulley stile is preferably made in two parts, *b* and *b*¹, upper and lower, and between them there is introduced the hereinafter described block, which in the shop is commonly called a wedge block, by reason of the inclination of portions of its working face, although it has no wedging function. This block *e*, to be described more particularly, is secured by a screw *f* to the heavy brace *d* at the line of the meeting rails of the two sashes, in each jamb, and has secured thereto, as by screws *b*², the corresponding ends of the pulley stile members *b* and *b*¹. The block *e* is preferably made as a casting and is formed on its rear face with protecting lugs *e*¹ which receive between them the heavy brace *d*, as clearly shown in Figure 1. In its outer or working face it is channeled vertically shown at *e*² in Figure 4, in registration with the channels or grooves *a*² and *a*³ in the face of the pulley stile. At its side edges it is rabbeted vertically, as at *e*³, to receive flush the edges of the main body of the jamb. On its front or working face it is formed with two oppositely inclined projections *e*⁴ and *e*⁵, the one, *e*⁴, for co-operation with the lower sash, as shown at the left-hand in Figure 1, and the other, *e*⁵, for co-operation with the upper sash, as shown at the right-hand in Figure 1. The ends of the middle portion *e*⁶ are reduced, as at *e*⁷, to receive the corresponding portions of the pulley stile so that they shall be flush with the middle part of the portion *e*⁶, and the ends of the side members, beyond the blocks or projections *e*⁴ and *e*⁵, are reduced as at *e*⁸, so as to receive flush the corresponding right and left-hand portions of the pulley stile, whereby the channels *a*² and *a*³ in the pulley stile are continued through the block *e* without shoulders which might interfere with the free movement of the sashes. It will be seen that the bottom member *c*² of the bottom rail of the upper sash *c* overlaps the ledge formed by the projection *e*⁵ at each

side and makes contact therewith, while the top member c^3 of the upper rail of the lower sash c^1 similarly overlaps the ledge formed by the block e^4 , and makes contact therewith when the sash is closed, whereby, when the sashes are closed, the narrow opening which would otherwise be left for the entrance of cold air, is closed effectually. It will further be observed that each sash bears only against the end of the ledges of the corresponding blocks e^4 , e^5 , and that there is no other contact between any part of either sash and the jamb, whereby friction between the sash and the jamb is avoided, thereby making the movement of the sashes easier and preventing the rubbing off of paint on the exposed faces of the pulley stiles. It will also be seen that by the provision of the solid blocks at the line of the meeting rails of the two sashes, the securing of the ends of the pulley stile members to such blocks, and the securing of the block through the pulley stile by the screw f to the brace d , the jamb is well supported and stiffened at this point and is prevented from yielding or distortion even in the case of high windows.

It will be understood that various changes in details of construction and arrangement can be made to suit different conditions of use and that, except as pointed out in the accompanying claims, the invention is not restricted to the particular construction shown and described herein.

I claim as my invention:

- 35 1. In a hollow metal window having a jamb with a removable, grooved pulley stile, and a heavy brace within the jamb, a heavy metal block secured to the brace, channeled in alignment with the grooves in the pulley stile and having the pulley stile secured thereto.
- 40 2. In a hollow metal window having a jamb with a removable, grooved pulley stile, and a heavy brace within the jamb, a heavy

metal block secured to the brace, channeled 45 in alignment with the grooves in the pulley stile, having the pulley stile secured thereto, and having on its rear face projecting lugs to engage the brace between them.

3. In a hollow metal window having a 50 jamb with a removable, grooved pulley stile, and a heavy brace within the jamb, a heavy metal block secured to the brace, channeled in alignment with the grooves in the pulley stile, having the pulley stile secured thereto, and reduced to receive flush the co-acting 55 portions of the pulley stile.

4. In a hollow metal window having a jamb with a two-part removable, grooved 60 pulley stile, and a heavy brace within the jamb, a heavy metal block secured to the brace between the two parts of the pulley stile, and having said two parts secured thereto.

5. In a hollow metal window having a 65 jamb and a pulley stile and a sash having the outside member of its meeting rail extended beyond the sash, a heavy metal block secured to the pulley stile, and having a projecting portion to bear against the sash and 70 to form a ledge for contact with the extended portion of the meeting rail.

6. In a hollow metal window having a jamb with a two-part removable, grooved 75 pulley stile, and a heavy brace within the jamb and sashes, and sashes having the outside member of each sash extended beyond the sash, a heavy metal block secured to the brace and having the two parts of the pulley stile secured thereto and having also projecting 80 portions to bear against the sides of the sashes and forming ledges to co-operate with the projecting portions of the meeting rails of the sashes when they are closed.

This specification signed this 23d day of 85 July A. D. 1925.

ALPHONsus FIEN.
